(57) **CLAIM**

The ornamental design for a condiment dispenser nozzle, as shown and described.

DESCRIPTION

FIG. 1 is a perspective view of a condiment dispenser nozzle showing my new design, the broken lines are for illustrative purposes only and form no part of the claimed design;

FIG. 2 is a front elevation view thereof;

FIG. 3 is a rear elevation view thereof; and,

FIG. 4 is a side elevation view thereof, the remaining sides being a mirror image.
